UNITED STATES PATENT OFFICE.

CHARLES S. BEARDSLEY, OF CANTON, OHIO.

RAZOR STROP.

Application filed December 18, 1918. Serial No. 267,279.

To all whom it may concern:

Be it known that I, CHARLES S. BEARDSLEY, a citizen of the United States, residing at Canton, in the county of Stark and State of Ohio, have invented certain new and useful Improvements in Razor Strops, of which the following is a specification.

The invention relates to strops for smoothing the sharpened edge of a razor blade so as to prepare and maintain it for the most efficient use; and the object of the improvement is to provide a strop which can be mounted for use upon the thumb and finger of one hand while the razor blade is held and manipulated by the thumb and fingers of the other hand.

Some sort of strop is desirable if not necessary for sharpening or smoothing the edge of a razor every time it is used, as well as several times during each use, to keep its edge in proper condition for keen and comfortable cutting; but unless a strop can be conveniently carried and supported, the inconvenience of using the same often prevents one from shaving himself or subjects one to the discomfort of a cutting, scraping or pulling action of a poorly prepared or maintained edge when self shaving is necessary.

The present improvement is specially useful for the short blades of safety razors in common use, which can be held between the thumb and fingers of one hand and stropped on a comparatively short and narrow surface; and involves the use of transverse stiffening means and inwardly facing finger holds on the under side of the ends of the strop for spanning the same between the tips of the thumb and forefinger of one hand.

A preferred embodiment of the invention is illustrated in the accompanying drawings, forming part thereof, in which—

Figure 1 is a plan view of the improved strop;

Fig. 2, a side elevation of the same mounted on the thumb and forefinger; and

Fig. 3, an under side view of the strop.

Similar numerals refer to similar parts throughout the drawings.

The strop 1 is made long enough to span the distance between the thumb and forefinger of the hand when the same are extended upward and spread apart to form a support for the strop, as shown in Fig. 2;

and is preferably made wide enough, at least, to include the length of the blades of ordinary safety razors.

The ends of the strop are preferably split to form the upper and lower laminations 2 and 3; and the stiffening means may be a metal plate 4 folded upon itself, with its upper fold 5 entered between the laminations of the strop and its lower fold 6 engaging the lower side of the lower laminations 3 thereof.

The stiffening plate 4 preferably extends the entire width of the strop and its upper fold 5 is somewhat longer than its lower fold 6, and may be secured to the lower lamination 3 of the strop by means of rivets 7 extending through the lower lamination of the strop, thus leaving the upper laminations thereof entirely free from the stiffening and securing means and shielding the same from contact with a razor blade.

The inwardly facing finger holds 8 may be in the form of crescent flanges 8 extending from the reverse side at each end of the strop, and as shown in the drawings, may be formed or stamped integral with the lower fold 6 of the stiffening plate 4. These holds are preferably inclined downward and inward so as to form an angular socket for more securely engaging the ends of the thumb and finger.

It is evident that by extending the upper fold 5 of the stiffening plate inward a substantial distance to overhang the inner sides of the thumb and finger, the strop will be held substantially horizontal throughout its entire length by the tension caused by spreading the thumb and finger apart; and also that the transverse stiffening plates at the ends of the strop serve to prevent a sagging of the sides of the strop and to hold the same to its work by presenting the entire length and width thereof to the blade when the strop is spanned between the tips of the thumb and fingers.

I claim:

1. A razor strop having transverse stiffening plates provided with inwardly facing crescent flanges forming thumb and finger holds on the reverse side at each end thereof. 105

2. A razor strop having means for transversely stiffening its end portions with integral inwardly facing and inclined crescent flanges forming thumb and finger holds on the reverse side thereof. 110

3. A razor strop having means for transversely stiffening its end portions with integral inwardly facing crescent flanges forming thumb and finger holds on the reverse side thereof. 5

4. A razor strop having inwardly facing and inclined crescent flanges forming thumb and finger holds on the reverse side at each end thereof. 10

5. A razor strop having its end portions split to form laminations, a transverse stiffening plate connected between the laminations at each end and inwardly facing crescent flanges formed upon the stiffening plates. 15

6. A razor strop having its end portions split to form laminations, a transverse stiffening plate connected between the laminations at each end and inwardly facing and inclined crescent flanges formed upon the stiffening plates. 20

7. A razor strop having its end portions laminated, a transverse stiffening plate connected between the laminations at each end and having a folded portion engaging the under surface of the strop and inwardly facing crescent flanges on the folded portion forming thumb and finger holds. 25

8. A razor strop having its end portions laminated, a transverse stiffening plate connected between the laminations at each end and having a folded portion engaging the under surface of the strop and inwardly facing and inclined crescent flanges on the folded portion forming thumb and finger holds. 30

CHARLES S. BEARDSLEY. 35
